COIN OPERATED VENDING MACHINE

George L. Duvall, Long Beach, Calif.

Application September 8, 1937, Serial No. 162,869

6 Claims. (CL 194—73)

This invention relates to vending machines, and more particularly to a coin-controlled vending machine for vending a measured quantity of merchandise such as peanuts and the like.

5 The general object of the invention is to provide a vending machine of the character stated, which is operated entirely by a coin, when deposited therein, and without the use of any manual-operating means.

10 Another object is to provide a vending machine of the character stated, which will throw out slugs and particularly iron slugs, washers and slugs lighter than the coin by which the machine is designed to be operated.

15 Other objects and advantages will appear hereinafter.

The invention is illustrated in the annexed drawings, which form a part of this specification, and in which—

20 Fig. 1 is a front elevation of my invention.

Fig. 2 is a transverse vertical section of my invention taken on line 2—2 of Fig. 14.

Fig. 3 is an enlarged front view of the lower portion of the machine as the same appears in

25 Fig. 2.

Fig. 4 is a vertical section taken on line 4—4 of Fig. 5 showing the coin chute.

Fig. 5 is a side elevation of the right side of the lower portion of the machine as shown in

30 Fig. 3.

Fig. 6 is a top plan view of Fig. 3.

Fig. 7 is a transverse vertical section taken on line 7—7 of Fig. 6.

Fig. 8 is a vertical section taken on line 8—8 of Fig. 6.

Fig. 9 is a cross section of the coin chute taken on line 9—9 of Fig. 6 with the coin chute in normal position or when a light coin is deposited therein.

40 Fig. 10 is a plan view of the coin chute in balanced position with a coin of the right denomination therein.

Fig. 11 is a cross section of the coin chute taken on line 11—11 of Fig. 10.

45 Fig. 12 is a horizontal section of the slug trap taken on line 12—12 of Fig. 4.

Fig. 13 is a plan view of the casing with the top wall thereof and parts mounted on said wall removed.

50 Fig. 14 is a vertical longitudinal section of the machine taken on line 14—14 of Fig. 1.

Fig. 15 is a plan view of the top plate of the casing of the machine.

55 Fig. 16 is a left side elevation of the spout of the magazine and the parts mounted thereon.

Fig. 17 is a perspective of the coin-actuated locking means for locking the measuring valve in its discharging position.

Referring more particularly to the drawings, in which corresponding parts are designated by the same reference characters in all of the views, 1 designates a casing constructed with a removable top wall 2 which rests at its edges upon in-turned flanges 3 formed on the front, side and rear walls of said casing near the upper edges 10 of said walls, so that the upper surface of said top wall is flush with the upper edges of said front, side and rear walls. The front wall 4 is also formed at its upper edge with a pair of in-turned flanges 5 under which are projected a pair of downwardly offset flanges 6 on the front edge of the top wall 2 when said top wall is placed in position in the top of the casing 1 upon the flanges 3. The top wall 2 is also formed with a pair of depending lugs 7 near its rear edge into 15 which are threaded screws 8 which extend through holes 9 in the rear wall 10 of the casing 1, whereby the top wall 2 with its flanges 6 engaging the casing flanges 5 is secured in position closing the top of the casing 1. The top 20 wall 2 is provided with an opening 11 and is formed with a circular flange 12 upstanding from the upper side of said wall and surrounding said opening. On said top wall 2 is mounted a globular glass magazine 13, which is provided in its 25 upper side with an inlet 14 and in its lower side an outlet 15, which outlet leads downwardly through an annular throat 16 depending from said lower side of said magazine and resting at its lower end upon the upper side of said top wall 30 2, with the lower end of said throat fitted within the annular flange 12 on said top wall. The magazine inlet 14 is surrounded by an annular flange 17 upstanding from the upper side of the magazine, which annular flange fits over a ring 35 18 formed with a cross bar 19 connected at its ends to opposite sides of said ring, at the lower edge thereof, through which cross bar, near its ends respectively, extend the upper ends of a pair of vertical rods 20, which extend through the 40 magazine, its outlet 15 and through the top wall 2, and the lower ends 21 of said rods are bent against the underside of said top wall. On the upper ends of the rods 20 are threaded nuts 22 45 which engage the upper side of the cross bar 19. A cap 23 fits over the inlet flange 17 and closes the magazine inlet 14, said cap being locked in its closed position by a key-controlled lock 24, which is connected at its lower end to the cross bar 19 and extends upwardly through 50 55

the top of the cap 23. On the rods 20 near the bottom of the magazine 13 is secured a guide 25 for preventing the merchandise from bridging or clogging the opening 11 in the top wall 2 and 5 for guiding the merchandise in the magazine, such as peanuts 26 or the like through said opening 11, as will be hereinafter more fully described.

The opening 11 in the top wall 2 of the casing 1 10 leads into the upper end of a discharge spout 27 depending from the lower side of said top wall, in the upper portion of which spout is mounted a rotatable measuring valve 28 in the form of a drum, with end walls 29, arcuate walls 30 and 31, 15 and an arcuate door 32, in which valve is located a measuring compartment 33. The end walls 29 are connected to the ends of the arcuate walls 30 and 31, while the arcuate door 32 is hinged at its upper edge by a hinge 34, to the lower edge of the 20 arcuate wall 30, and the lower edges 35 and 36 of the arcuate wall 31 and door 32, respectively, meet when the valve 28 is in its normal receiving position as shown in Fig. 7 of the drawings. The upper portions 37 and 38 of the front wall and 25 rear wall, respectively, of the spout 27 are arcuate, and within said upper wall portions are turnably fitted the arcuate valve wall 30, door 32 and the arcuate valve wall 31, respectively, the valve 28 being secured on a shaft 39 which extends 30 through and is journaled in bearings 40 of the side walls 41 of the spout 27, whereby said valve is rotatably mounted in the upper portion of said spout. The upper ends of the arcuate valve walls 30 and 31 are spaced apart to provide an entrance 35 42 into the valve measuring compartment 33, which entrance normally rests directly under the opening 11 in the top wall 2 of the casing 1, in the receiving position of the valve 28 and its said measuring compartment, as shown in Fig. 7.

40 The measuring compartment 33 is formed in the valve 28 by walls 43 and 44, the wall 43 extending from the upper end of the arcuate wall 31 to the valve shaft 39, and the wall 44 extending from the upper pivoted end of the door 32 to said shaft.

45 On one end of the valve shaft 39 is keyed a crank 45 which is held on said shaft by a nut 46 threaded on said end of said shaft. The valve 28 is positioned and detachably secured on said valve shaft 39 by a pair of cotter pins 47 (Fig. 8), which are driven through said shaft and wedged against the inner sides of the valve end walls 29, respectively. The crank 45 is formed with a projecting arm 48 to which is connected the upper end of a spring 49, the lower end of said spring being connected to a pin 50 on the lower portion of the spout 27, which spring normally holds the valve in the position shown in Fig. 7 with its measuring compartment 33 in position to receive its capacity of merchandise from the magazine 13.

50 A lock 51 is provided for locking the valve door 32 closed until the proper time to open said door, as will be hereinafter more fully described, which lock comprises a locking bar 52, a trigger 53 and a coin-actuated trip lever 54. The locking bar 52 is pivotally mounted within the spout 27 below the valve 28 and is curved to fit the lower side of the arcuate wall 31 and door 32 of said valve, said locking bar being formed at its ends, respectively, with a pair of apertured ears 55 through which 55 loosely extends a pivot rod 56 for said locking bar, which rod is secured at its ends in the lower portions 57 and 58 of the front and the rear walls, respectively, of the spout 27. On the inner side edge of the locking bar 52 is formed a depending arm 59 to which is pivoted, as at 60, the inner end

of the trigger 53, and on the outer edge of said locking bar is formed a cam-engaging arm 61 which extends outwardly through an opening 61' in one side of the spout 27 under a cam 62 formed on the lower part of the crank 45, the engagement of said arm and cam positively locking the locking bar 52 in its locking position, while the measuring valve 28 is in its normal position for receiving merchandise from the magazine 13, as shown in Fig. 7 of the drawings. The trigger 53 is provided 10 with notches 63 and 64 near its outer end to respectively receive the upper edge of the trip lever 54, for setting said trigger to be released for permitting the locking bar 52 to swing of its own weight into unlocking position in the manner 15 hereinafter more fully described. The trip lever 54 is fulcrumed at 65 to the outer side of a lower portion 66 of a side wall 41 of the spout 27 and is engaged at its forward end by one arm of a coil spring 67, the other arm of which spring is connected to said spout, as at 68. Said lower side wall portion 66 is provided with an opening 68 through which extends the outer end portion of the trigger 53 for guiding said trigger, so that the upper edge of the trip lever 54 may engage one of 20 the trigger notches 63 or 64. The rear end of the trip lever 54 extends upwardly and is bifurcated, as at 70, to receive a proper coin for depressing said end of said lever to disengage the upper edge of said lever from the trigger notch 63 or 64 to 30 release the trigger 53 for unlocking the valve door lock 51 in the manner and for the purpose herein-after more fully described.

On the upper side of the top wall 2 of the casing 1, at the front and at the right of said casing is 35 mounted a coin-receiving chute 71 provided with a coin slot 72 leading from its upper end in the front of the chute downwardly to a slot 72' in said top wall. On the rear of said chute, within said coin slot 72, is pivoted a coin-actuated lever 73, on 40 a pivot 74, near the lower end of said chute. Said lever 73 is formed with a relatively long vertical lever member 73', a coin-engaging arm 75 extending forwardly from the upper end of said lever member, a cam 76 extending rearwardly from the 45 lower end of said lever member, and a rear connecting arm 77 extending upwardly from the rear end of said cam. The forward end 78 of the coin-engaging arm 75 rests in the upper end of the chute slot 72 at the upper edge thereof, and is 50 inclined downwardly in a rearward direction to be engaged by the edge of a coin for directing the coin inwardly and downwardly through the coin chute slot 72 and the slot 72' in the top wall 2, when the coin is deposited in the upper and front 55 end of the coin chute slot 72. The lower fixed edge 79 of the upper end of the coin chute slot 72 lies below and slightly forwardly of the inclined coin-engaging end 78 of the coin-actuated lever 73. The rear arm 77 of the coin-actuated lever 60 73 is connected to the forward end of a link 80, which is connected at its rear end to the upper end of a lever 81 pivoted at 82 in a bracket 83 depending from the lower side of the top wall 2 of the casing 1. To the lower end of the lever 81 65 is connected the forward end of a link 84, in the rear end of which is secured a pin 85 which projects into a concentric slot 86 in the valve crank 45. A spring 87 is connected at its forward end to the top wall 2, at 88, and at its rear end to the 70 forward end of link 84, as at 89, which spring holds the coin-actuated lever 73 in its normal coin-receiving position and the cam 76 and link 84 in their normal retracted positions, as shown in Fig. 5 of the drawings, in which position of the 75

link 84 the crank spring 49 holds the valve crank 45 in position with the rear end of its slot 86 against the pin 85 in the rear end of said link, and thus holds the measuring valve 28 in its normal position, with its valve measuring compartment 33 in its uppermost position for receiving merchandise from the magazine 18.

Below the coin slot 72' and the coin chute 71, a slug trap 90 is mounted on the under side of the top wall 2 of the casing 1, which slug trap includes a fixed vertical guide wall 91, a flat spring 92, a pocket 93, a detent 94 and a magnet 95. The guide wall 91 and the flat spring 92 are secured at their upper ends to the under side of the top wall 2, at 96 and 97, respectively, with the inner sides of said guide wall and said flat spring flush with the sides, respectively, of the coin slot 72' in said top wall. The pocket 93 is hinged at its upper end by hinges 98, to the guide wall 91, so that the weight of said pocket holds it in its normal coin-receiving position, with the inner edges of its vertical front wall 99 and bottom wall 100 against the inner side of the guide wall 91, and its outer side wall 101 spaced from the inner side of said guide wall, as shown in Fig. 4 of the drawings, the rear of said pocket being open to provide an opening 102 through which extends the cam 106 on the lower end of the member 74 of the coin-actuated lever 73, as shown in Fig. 12 of the drawings. The bottom wall 100 of the pocket 93 is inclined downwardly in a rearward direction, as shown in Fig. 5. The detent 94 is pivoted within the pocket 93 forwardly of the flat spring 92 on a pivot 103, which is secured at its front end in the front wall 99 of said pocket and at its rear end in a lug 104 on the inside of the side wall 101 of said pocket, so that the inner edge of said detent faces the inner side of the guide wall 91, while the outer edge of said detent extends through a vertical slot 105 in said side wall 101 of said pocket. Said detent is formed with a cam 106 along its inner edge, the highest point of which cam being at the lower end of said edge, while said detent is formed, at its upper end and at its inner edge, with a prong 107, said cam engaging the guide wall 91 and resting between said guide wall and the flat spring 92, which extends downwardly into said pocket, and said prong being withdrawn from between said guide wall and said flat spring, when the pocket 93 is in its coin-receiving position, as shown in Fig. 4. The magnet 95 is secured within the pocket 93 adjacent the inner side of the outer wall 102 of said pocket by a screw 108, which extends through said wall.

From the opening 102, at the rear end and at the lower end of the slug-trap pocket 93, leads a balanced coin rock-chute 110, inclined downwardly in a rearward direction, to the bifurcated rear end 70 of the trip lever 54, which chute is secured on a U-shaped rock frame 111 comprising a pair of lever members 112 and 113 and a side member 114 connecting the outer ends of said lever members, the inner ends of said lever members being connected to said chute 110 near its ends respectively and at the upper edge thereof. The chute 110 and its supporting frame 111 are pivotally mounted on the lower ends of a pair of suspension arms 115 and 116, depending from the top wall 2, by means of a pair of pivot set screws 117 and 118 threaded in the lower ends of said suspension arms respectively, which screws are formed with conical precision end bearings 119 and 120, respectively, which are adjustably seated in bearing apertures 121 and 122, respective-

ly, in the lever members 112 and 113 respectively of the chute rock frame 111. The rock chute 110 is provided in its outer side wall with a discharge opening 123, which is controlled by a swinging gate 124 hinged at its lower and upper edges by a pair of hinges 125 to the outer wall of said chute, at the rear side of said discharge opening, so that said gate may swing into said discharge opening to allow a proper coin to pass through the chute, as shown in Fig. 10, or swing across the chute at an angle forwardly from its hinges 125 to discharge a light slug through said discharge opening, as shown in Figs. 6 and 9. The gate 124 is formed with an arm 126 extending rearwardly from its rear edge outside of the outside of the chute 110 for engaging a fixed vertical arm 127 secured at 128 to the forward end of a coin delivery chute 129, for swinging said gate into the chute discharge opening 123, when a proper coin enters the chute 110 and swings said chute and its supporting frame 111 on the pivot screws 117 and 118 against a weight 130 in the form of a set screw seated in the frame connecting member 114, which weight normally holds said supporting frame and chute in such position that the gate 124 is swung across the chute forwardly at an angle from its hinges 125, as shown in Figs. 6 and 9, so that a light coin will be directed by said gate from the chute through said discharge opening. The measuring valve crank 45 is formed with an arm 45' which engages the lever member 113 of the chute frame 111 and holds the chute 110 in position with the coin gate 124 closed to discharge a proper coin from said chute when the valve 28 closes prematurely and fails to discharge the merchandise.

The delivery chute 129 leads from the bifurcated end 70 of the trip lever 54 downwardly at an incline across the rear side of the spout 27, the chute being curved at its upper end at 130 to extend from the right side of said spout, where said trip lever is located to the rear of said spout. The bottom wall of the coin-delivery chute 129 is cut away from the rear end of the chute for a short distance to provide a discharge opening 129' through which coins drop from the rear end of the chute.

Locking means 131 are provided for locking the measuring valve 28 in the position to which it is turned to allow the valve door 32 to swing down on its hinge 34 to dump a measured quantity of merchandise from the valve measuring chamber 33, when a proper coin is deposited in the coin chute 71, until said coin has rolled down the delivery chute 129 and has been collected in the machine, during which time the valve door 32 is allowed to remain open long enough to dump completely the measured quantity of merchandise from the valve measuring chamber 33. Said locking means 131 includes a locking lever 132, a trigger 133, a coin-actuated trigger trip lever 134, an auxiliary coin-actuated trip lever 135, and a trigger-setting crank 136. The locking lever 132 extends horizontally across the rear of the spout 27 and is pivoted at 137 to the upper portion 38 of the rear wall of said spout, said locking lever being formed at one end with a latch 138 which extends through a slot 139 in said upper portion 38 of the rear wall of the spout 27, for projecting into a notch 140 in the outer side of the arcuate wall 31 of the measuring valve 28, under the influence of a spring 141 between said upper portion 38 of the rear wall of the spout 27 and a flange 142, on the inner edge of the locking lever 132, at the side of the pivot 137 of said lever 75

opposite the side at which said latch 138 is located. The trigger 133 is pivoted at 143 to a vertical bracket 144, formed on the rear end of the coin delivery chute 129, and is connected at its upper end to one end of a spring 145 which is connected at its other end to an arm 146 depending from the top wall 2. The trigger-setting crank 136 comprises a crank rod 136' bent at its ends in the form of a pair of crank arms 147 and 148, respectively, said crank rod being journaled in bearings 149 and 150, on the rear of the spout 27 and in the bracket 144, respectively. The crank arm 147 is connected at 151 to the rear end of a link 152, which link is connected at its forward end to the pin 85 in the rear end of link 84. The crank arm 148 is formed at its upper end with a horizontal finger 153 for engaging the forward edge of the trigger 133 for setting said trigger in the manner hereinafter more fully set forth. The coin-actuated trigger trip lever 134 is pivoted at 154 to the bracket 144 and is formed with a lug 155 to be engaged by the lower end of the trigger 133 to hold said trigger out of engagement with the locking lever 132, so that the spring 141 may hold said locking lever in position with its latch 138 engaging the notch 140 and locking the measuring valve 27 in its dumping position, while a proper coin travels past the forward end 78 of the coin-actuated lever 73 through the coin chute 71, slug trap 90, rock-chute 110, and delivery chute 129, during which time the door 32 remains open long enough to dump completely a measured quantity of merchandise from the valve measuring compartment 33. A flat spring 156 is secured at one end at 157 to the bracket 144, and bears at its other end upon the upper edge of the weighted forward arm 158 of the coin-actuated trigger trip lever 134 for normally holding said lever in position with its rear arm and lug 155 raised, and so that the lower end of the trigger 133 will engage the forward edge of said lug and hold said trigger out of engagement with the locking lever 132, to enable the spring 141 to swing said locking lever to cause its latch 138 to engage the notch 140 and lock the measuring valve 27 in its open position. On the rear end of the rear arm of the coin-actuated trigger trip lever 134 is formed a short depending trip-lever coin chute 159, the upper end of which rests below the rear end of the coin-delivery chute 129 in position to receive a coin as it drops through the discharge opening 129' from the rear end of said coin-delivery chute, said trip lever chute being curved downwardly toward and to a point below the lower end of an auxiliary trip-lever coin chute 160 depending from the pivoted end of the auxiliary coin-actuated trigger trip lever 135, in position also to receive said coin as it drops through the discharge opening 129' from the rear end of said coin delivery chute 129 into said trip-lever chute 159, said auxiliary coin-actuated trigger trip lever 135 being pivoted at its forward end to the under side of said coin-delivery chute 129 at 161. The rear end 162 of the auxiliary coin-actuated trigger trip lever 135 extends through a slot 163 in a bracket 164 standing from the upper edge of the rear arm of the coin-actuated trigger trip lever 134, so that should the coin passing through the trip lever chute 159 and bearing upon the curved transverse wall 159' of said chute fail to depress the rear arm of the trigger trip lever 134 sufficiently to disengage the lug 155 from the lower end of the trigger 133, the coin, guided by the curvature 75 of said transverse wall 159' into engagement with the transverse vertical wall 165 of the auxiliary trip-lever coin chute 160, as the coin drops through said chute, will swing the auxiliary trigger trip lever 135 on its pivot 161 and cause the rear end of said trip lever 135 to engage the lower end of the slot 162 and depress the rear arm of the trigger trip lever 134 sufficiently to disengage said lug 155 from the lower end of said trigger 133. A stop arm 144' extends from the bracket 144 to be engaged by the lower edge of the trip lever 134 to limit the downward movement of the rear arm of said lever.

In the casing 1, opposite the slug discharge opening 123 of the balanced coin chute 110, is mounted a slug discharge chute 166, which leads 15 downwardly to an opening 167 through the right side wall 168 of a pocket 169 formed in the front wall 4 of the casing 1, said chute being formed with a flange 170 at its lower end which is bolted at 171 to said pocket side wall whereby said chute 20 is mounted as aforesaid.

A merchandise delivery chute 172 is mounted in the casing 1, and leads from the lower end of the merchandise spout 27 to the inner end of a merchandise delivery spout 173, which extends 25 forwardly through an opening 174 in the rear wall 175 of the pocket 169 into the lower part of said pocket, said spout being formed at its inner end with an external flange 176, which rests against the inner side of said pocket wall, 30 and said chute 172 being formed at its forward end with an external flange 177, which rests against the rear side of said spout flange. The chute flange 177 is bolted to the spout flange 176, and said spout flange is bolted to the rear pocket wall 175 by bolts 178, whereby the chute 172 and the spout 173 are detachably mounted in position as aforesaid. The spout 173 is normally closed by a gate 179, which is detachably hinged at its upper end, at the upper end of the chute 40 opening 175, by hinge pins 180 formed thereon at the sides thereof, which pins rest in notches 181 in the upper end of the spout flange 176, so that the lower end of the gate 179 rests upon the lower end of the spout 173 to close said spout. 45 The gate 179 is provided with slots 182 through which the vended merchandise may be observed in said spout by the vendee.

The lower wall 183 of the casing 1 is detachable and is locked in position against a flange 50 184 in the lower end of said casing, by a key-controlled lock 185, which engages a bolt 186 extending through a bracket 187 secured to the inner side of the rear wall 175 of the pocket 169.

On the under side of the top wall 2, at the forward side of the opening 11 in said wall, is mounted a slide plate 190 in guides 191 secured to the under side of said top wall, which plate is formed on its lower side with a depending apertured lug 192 through which extends a rod 60 193, secured at its forward end in a lug 194 depending from the under side of said top wall 2, which rod is surrounded by a coil spring 195 bearing at its ends against the lugs 192 and 194 respectively. Said spring usually projects said 65 plate 190 inwardly towards the measuring valve 28, so that the inner edge of said plate rests inwardly of the opening 11 and the measuring chamber 33. Said inner edge of the plate 190 forms a yielding forward edge of the opening 11 70 so that if any of the merchandise, and particularly metal prizes, should be caught between said edge and the forward end of the arcuate wall 31 of the measuring valve 28, when said valve 75 is rotated to discharge the merchandise from

the measuring chamber 33, the slide plate 190 will yield and slide forwardly against the tension of the spring 195 and allow the forward end of said arcuate wall 31 to slide past said caught merchandise as said forward end approaches the upper end of the upper portion 31 of the forward wall of the spout 27, thus avoiding jamming of the valve 28.

The operation, uses and advantages of my invention are as follows:

To purchase a measured quantity of merchandise, such as peanuts, a purchaser inserts a proper coin, for example, a penny, through the slot 72 in the upper forward end of the coin chute 71 and presses the coin inwardly into said chute between the lower fixed edge 79 of said chute and the inclined forward upper edge 78 of the coin-actuated lever 73, whereupon said lever is swung clockwise (Fig. 5) on its pivot 74 and the crank 45 and its arm 45' together with the valve shaft 39 are turned counter-clockwise against the tension of spring 49, through the medium of the cam 76, arm 77, link 80, lever 81 and link 84, by the engagement of the link pin 85 with the rear end of the crank slot 86, so that the low part of the cam 62 is brought over the locking bar arm 61 while the trigger setting crank 136 is swung clockwise (Fig. 5) by the link 152 and crank arm 147, and the finger 153 of the crank arm 148 engages the forward edge of the upper arm of trigger 133 and swings said trigger counterclockwise (Fig. 16) until the lower end of said trigger escapes the lug 155 of trip lever 134 and engages the forward edge of said lug, the spring 156 yielding to allow said trip lever to be swung on its pivot 154 for the escape-ment of the lower end of said trigger over said lug. The forward movement of the cam 76, by the lever 73, when actuated by the coin as afore-said, causes said cam to engage the rear edge of the side wall of the pocket 93 and swing said pocket open for the purpose hereinafter de-scribed. The setting of said trigger by the en-gagement of its lower end with lug 155 with-draws said trigger from the locking lever 132 and permits the spring 141 to swing the locking lever 132 to project its latch 138 into the valve notch to lock said valve when rotated to bring said notch into register with said latch, in the man-ner and for the purpose hereinafter set forth. A measured quantity of merchandise having dropped from the magazine 13 through the outlet opening 11 in wall 2 into the valve measur-ing chamber 33, turning of the valve shaft 39, as aforesaid, turns the measuring valve 28 counter-clockwise (Fig. 14) until the door 32 of said valve measuring chamber reaches its lower-most or discharging position, in which position of the valve the notch 140 is brought opposite the latch 138 of locking lever 132, whereupon the spring 141 swings said locking lever on its pivot and projects said latch into said notch and locks the valve 28 against turning in either di-rection, thus locking the measuring valve 28 in position for discharging the measured quantity of merchandise from its measuring chamber 33. Turning of the crank 45 and its arm 45', as aforesaid, removes said arm from the member 113 of the coin chute frame 111, so that a proper 70 coin upon entering the rock chute 110 will swing said chute into vertical position, as shown in Fig. 11, for the purpose hereinafter described. When the coin, deposited in the upper end of the coin chute 71, escapes the inclined forward edge 78 of the coin-actuated lever 73, it drops

down through said chute through opening 72' in top wall 2, between wall 91 and flat spring 92 of slug trap 90, into said slug trap past the prong 107 of detent 94 and against the cam 106 on the lower end of said detent, whereupon the coin 5 swings said detent counterclockwise (Fig. 4), the detent prong 107 swinging over the upper edge of the coin, and allows the coin to drop past said detent into the bottom of the slug trap pocket 93, which has swung back to its 10 closed position, as shown in Fig. 4, after having been swung open, by the cam 76, when the coin was deposited in the coin chute and the coin-actuated lever 73 was swung on its pivot as afore-said, for the purpose hereinafter more fully de-scribed. The coin, upon dropping into the bot-15 tom of the slug trap pocket 93, rolls rearwardly down the inclined bottom wall 100 of said pocket, out of said pocket, into the upper forward end of the balanced rock chute 110, which is in the 20 position shown in Fig. 9 of the drawings, and the weight of said coin swings said chute and its frame 111 on the pivots 117 and 118 into the position shown in Fig. 11 and in Fig. 10, during 25 which operation the lower rear end of said chute 25 110 is brought into registration with the bifurcated rear end 70 of the coin-actuated trip lever 54, while the coin gate 124 is swung outwardly into the coin discharge opening 123 of said chute by the engagement of the gate arm 126 with the 30 fixed arm 127 (see Fig. 10), providing a free pas-sage in the chute past said gate, whereupon the coin rolls rearwardly down the chute 110 out of its rear end into the bifurcated end 70 of the coin-actuated trip lever 54, and the balanced 35 rock chute 110 and frame 111 swing back to their normal position under the influence of weight 130, as illustrated on Fig. 9. The weight of the coin in said bifurcated end 70 swings the coin-actuated trip lever 54 clockwise on its pivot 40 65 and disengages the upper edge of said lever from the notch 63 or 64 of the trigger 53, which trips said trigger and allows the locking bar 52 to swing down on its pivot 56 away from the door 32 of the measuring valve 28, the lower part of 45 the cam 62 above the cam-engaging arm 61 allowing said arm to swing up also to allow said locking bar to swing down, whereupon said door 32 and the lower wall 44 of the measuring cham-50 ber 33 swing down on their hinge 34 and dis-charge the measured quantity of merchandise from said measuring chamber downwardly through the spout 27 and delivery chute 112 into the delivery spout 113, where the merchan-dise is arrested by the delivery gate 179, the arcu-55 ate door 32 swinging down into the lower part of the spout 27 against the lower arcuate portion 57 of the front wall of said spout. The dis-charged merchandise may be removed from the delivery spout 113 by the purchaser upon lifting 60 the gate 179, on its hinges 180, by means of the handle 179' on the forward end of said gate. The deposited coin, after swinging the trip lever 54 to trip the trigger 53 to release the locking 65 bar 52, rolls out of the bifurcated end 70 of said trip lever into the forward upper end of the coin-delivery chute 129 and down said chute, where-upon the spring 67 swings the trip lever 54 counter-clockwise until its upper edge engages the lower side of the trigger 53 at the rear of 70 the notch 64. The coin rolling down the de-livery chute 129 rolls out of the lower rear end of said chute through the discharge opening 129' and drops through the trip-lever chute 159 and the auxiliary trip-lever chute 160 into the bottom 75

of the casing 1 upon the bottom wall 183 of said casing and is thus collected, and as the coin drops through said chutes 159 and 160 it bears at its edge with its weight first upon the transverse wall 159' of the trip-lever chute 159, and generally this action of the coin depresses the rear end of the trigger trip lever 134 and raises the forward weighted end 158 of said lever against the tension of spring 156 and disengages the lug 155 of said lever from the lower end of the trigger 133 and trips said trigger, whereupon the spring 145 swings said trigger clockwise (Fig. 16) and the forward edge of said trigger, above its pivot 143, engages the rear edge at the adjacent end of locking lever 132 and swings said locking lever on its pivot 137 against the tension of the spring 141 and withdraws the lever latch 138 from the valve notch 140, and the measuring valve 28 is turned clockwise (Fig. 7) by the crank spring 49, through the medium of crank arm 48, crank 45 and valve shaft 39 back to its initial receiving position, as shown in Fig. 7, during which operation the valve door 32 engages the lower end of the upper arcuate portion 31 of the front wall of the spout 27, and said door and lower wall 44 of measuring chamber 33 are swung back to their normal position with said wall, closing the lower end of said measuring chamber, while the high part of cam 62 is brought against the arm 61, swinging the locking bar 52 back into locking position against the door 32. Should the coin, as it drops through the trip-lever chute 159, as aforesaid, fail to depress the rear end of the trigger trip lever 134 and trip the trigger 133, the rear end of said trip lever will nevertheless be depressed and the trigger tripped, by the engagement of the rear end 162 of the auxiliary trip lever 135, with the lower edge of the slot 163, in the rear end of said trigger trip lever 134, under the influence of the weight and rolling inertia of the coin, the edge of which bears against the transverse wall 165 of the auxiliary trip-lever chute 160 and swings said auxiliary trip lever 135 counterclockwise as the coin drops through the lower ends of said trip-lever chute 159 and auxiliary trip-lever chute 160 into the bottom of the casing 1, and is thus collected. When the coin has performed its function in operating the machine and has been collected, as aforesaid, the machine is ready to receive another coin and to vend another measured quantity of merchandise as above described.

Should a slug of lighter weight than the weight of the proper coin be deposited in the coin-receiving chute 71, it will drop through said chute and the slug trap 90 and roll into the balanced chute 110 in the same manner as a proper coin, but its weight will not be sufficient to swing said chute 110 and its frame 111 on the pivots 117 and 118, and the gate 124 will remain in its closed position across the chute 110, so that said light slug, in rolling down said chute, will be deflected by said gate and ejected through the discharge opening 123 in the outer side of said chute, into the slug-discharge chute 166, down which chute said light slug will slide and pass out of the lower end thereof through the opening 167 into the bottom of the pocket 169, in the front of the machine, where it will be exposed to view and aid in the detection of the depositor of said slug.

Should a washer, or slug with a hole in it, be deposited in the coin chute 71, it will drop through said chute between the slug-trap wall

81 and flat spring 92, into the slug trap 90, against the cam 106 of the detent 84, and swing said detent counterclockwise (Fig. 4) which will project the detent prong 107 through the hole in said slug and trap said slug in said slug-trap 81 and prevent said slug from operating the machine. Said slug will remain trapped in the slug trap until another or succeeding coin or slug is deposited in the coin-receiving chute 71, and the pocket 93 of said trap is swung open at its lower end, on its hinges 98, by the engagement of the cam 76 with the rear end of the outer side wall 101 of said pocket, when the coin-actuated lever 73 is swung clockwise by the engagement of said succeeding coin or slug with the inclined upper forward edge 78 of said coin-actuated lever, whereupon the detent prong 107 will be withdrawn from the hole in the slug, as said pocket is swung open, and the released slug will drop down between the trap wall 91 and flat 20 spring 92, out of the lower open end of the slug trap 90, into the slug-discharge chute 166 and down said chute through the outlet opening 167, into the bottom of the front pocket 169 of the casing 1.

Should an iron slug be deposited in the coin-receiving chute 71, it will be arrested and held by the force of the magnet 95 in the slug trap 90, between the trap wall 91 and flat spring 92, until a succeeding coin or slug is deposited in the 30 coin-receiving chute 71 and the trap pocket 93 is swung outwardly on its hinges 98, by the engagement of the cam 76 with the rear edge of the pocket side wall 101, as the coin-actuated lever 73 is swung on its pivot by the engagement 35 of said succeeding coin or slug with the inclined forward edge 78 of said coin-actuated lever, during which outward swinging operation of said pocket and the magnet, away from the slug, the force of the magnet will be reduced sufficiently 40 to release the iron slug, so that said slug will drop from between the lower end of the flat spring 92 and the trap wall 91 out of the lower end of the slug trap 90, into and down the slug discharge chute 166 and out through the outlet 45 opening 167, into the bottom of the front pocket 169 of the casing 1.

Should the measuring valve 28, upon deposit of a proper coin in the coin-receiving chute 71, be swung prematurely, by spring 49, back to its 50 normal merchandise-receiving position, without discharging its measured quantity of merchandise, the crank 45, swinging back with said valve, will swing the lower end of its arm 45' against the outer portion of the upper edge of the lever 55 member 113 of the balanced chute frame 111, and swing the balanced chute 110 back to its normal coin-receiving position (Fig. 9) and prevent the coin gate 124 from being swung out of its closed position in the chute, before the coin 60 rolls down said chute to said gate, so that said proper coin when it reaches said gate will be deflected by said gate out of said chute through the discharge opening 123, into the slug discharge chute 166, down which said coin will slide and will pass out through the opening 167 into the bottom of the front pocket 169 of the casing, where the depositor of said coin may recover the same, thus returning a proper coin to its depositor, when the machine fails to function.

I do not limit my invention to the exact construction herein shown, since various changes therein may be made within the scope of the invention.

I claim:

1. A vending machine comprising a magazine for merchandise, a valve for receiving and measuring a quantity of merchandise from said magazine and for discharging said measured quantity of merchandise, coin-actuated means for moving said valve from its receiving and measuring position to its discharging position, means for automatically locking said valve when moved into its discharging position, means for automatically locking said valve closed when moved into its discharging position, coin-actuated means for automatically releasing said last locking means to allow said valve to open, while locked in its discharging position, to discharge a measured quantity of merchandise, and coin-actuated means for automatically releasing said means for locking said valve in its discharging position, when a measured quantity of merchandise is discharged by said open valve, and means for automatically returning said valve to its receiving and measuring position when said valve is unlocked from its discharging position.

2. A vending machine comprising a magazine for merchandise provided with an outlet in its lower end, a plate upon which the lower end of said magazine rests, said plate being provided with an outlet opening which registers with said magazine outlet, a measuring valve mounted below said outlet opening in said plate, said measuring valve being formed with a measuring compartment provided with an inlet opening which registers with said outlet opening in said plate, when said valve is in measuring position, a slide plate mounted on the under side of said plate, spring means for projecting the inner edge of said slide plate inwardly of one edge of said outlet opening in said plate and over one edge of the inlet opening in the measuring compartment, when said valve is in its measuring position, and said spring means yielding to permit said slide plate to slide outwardly from said edge of said outlet opening in said plate, when merchandise is caught between the inner edge of said slide plate and the opposite edge of said inlet opening of said measuring compartment, so that said caught merchandise will be caused by the opposite edge of said inlet opening, as it approaches the inner edge of said slide plate, to release said caught merchandise into said measuring compartment when said valve is rotated into discharging position, coin-actuated means for rotating said valve into discharging position, coin-actuated means for automatically enabling said valve to discharge its measured quantity of merchandise when the valve is rotated to its discharging position, and means for automatically returning said valve to its measuring position, when it has discharged its measured quantity of merchandise.

3. In a vending machine, a rotary valve for receiving and discharging merchandise, coin-actuated means for rotating said valve into discharging position, a spring-pressed locking lever

formed with a latch for engaging a notch in said valve for locking said valve when rotated into its discharging position, a trigger, a trigger spring for swinging said trigger against said locking lever for normally holding said locking lever in position with its latch withdrawn from said notch in said valve and unlocking said valve, a trigger trip lever, a trigger-setting crank, means whereby said trigger-setting crank is swung, by said coin-actuated means, for engaging and swinging said trigger to engage said trigger trip lever for setting said trigger, and for disengaging said trigger from said valve locking lever, so that said lever will be swung by its spring to project its latch into said valve notch to lock said valve in its discharging position, and a trigger trip lever into which a coin may drop from said coin-actuated means, to swing said trigger trip lever to trip said trigger, so that said trigger spring will swing said trigger to engage said valve locking lever to disengage said lever latch from said valve notch, to unlock said valve, and means for returning said valve to its receiving position, when said valve is unlocked.

4. In a vending machine, as claimed in claim 25 3, an auxiliary trigger lever formed with an auxiliary chute into which the coin also drops from the delivery end of said delivery chute and swings said auxiliary trigger lever against said trigger trip lever to insure sufficient swinging 30 movement of said trigger trip lever to trip said trigger.

5. A vending machine including a magazine for merchandise, means for receiving and measuring a quantity of the merchandise from said magazine and for discharging said measured quantity of merchandise, coin-actuated means for exclusively operating said receiving, measuring and discharging means for discharging said measured quantity of merchandise, means for returning a proper coin deposited in said coin-actuated means when said receiving, measuring and discharging means fails to discharge said measured quantity of merchandise, and means carried by said receiving, measuring and discharging means for actuating said coin-returning means as aforesaid.

6. A vending machine including a magazine for merchandise, a measuring valve for receiving and measuring a quantity of merchandise and for discharging said measured quantity of merchandise and coin-actuated means for exclusively operating said valve for discharging said measured quantity of merchandise, means for locking said valve in position for discharging said measured quantity of merchandise, means for returning a proper coin deposited in said coin-actuated means, when said means fails to return said valve sufficiently to be locked by said locking means in its discharging position, and means carried by said measuring valve for actuating said coin-returning means as aforesaid.

GEORGE L. DUVALL.
